(57) **CLAIM**

The ornamental design for a spinal cage, as shown and described.

DESCRIPTION

FIG. 1 shows a front-top isometric view of a spinal cage; FIG. 2 shows a rear-bottom isometric view of the spinal cage of FIG. 1; FIG. 3 shows a front view of the spinal cage of FIG. 1; FIG. 4 shows a rear view of the spinal cage of FIG. 1; FIG. 5 shows a right side view of the spinal cage of FIG. 1; FIG. 6 shows a left side view of the spinal cage of FIG. 1; FIG. 7 shows a top view of the spinal cage of FIG. 1; and, FIG. 8 shows a bottom view of the spinal cage of FIG. 1. The broken lines in the drawings illustrate portions of the spinal cage and form no part of the claimed design. The dash-dot broken lines illustrate portions of the spinal cage. The dot-dash lines illustrate the bounds of the claim. None of the broken lines form part of the claimed design.
